ABSTRACT OF THE DISCLOSURE

In association with a method and equipment for collecting emissions during the pushing cycle of coke from a coke oven, fume doors in a collecting main are opened in a prescribed sequence that includes lowering the suction in the collecting main, opening the fume main, closing the fume door, and restoring the suction in the collecting main. An atmospheric vent and damper in the collecting main suction conduit are used to reduce and to restore the suction. The fume doors are not opened or closed when high suction conditions exist in the collecting main.

BRIEF SUMMARY OF THE INVENTION

A system and method is described for controlling emissions while pushing of coke from a coke oven in a battery equipped with apparatus for collecting and removing effluent while pushing coke as described in application Ser. No. 170,926, filed Aug. 11, 1971, now Pat. 3,785,933.

The system of the present invention is adaptable to other apparatus for collecting emissions that operate in a similar manner and is not limited exclusively to the apparatus in the application, which is mentioned only to assist those skilled in the art in understanding the present invention. The system includes basically an electrical control system that actuates the damper and vent valves of the collecting main when the apparatus of the mentioned application is positioned at an oven that is ready to be pushed.

For a further understanding of the invention and for features and advantages thereof, reference may be made to the following description and the drawing which illustrates a preferred embodiment of a system in accordance with the invention.

BRIEF DESCRIPTION OF THE DRAWING

The drawing, comprising two sheets of bristol board, shows schematically and in simplified form a control system in accordance with my invention.

DETAILED DESCRIPTION

Such apparatus shown schematically in FIG. 2 includes a hood portion that is mounted to a coke guide car carrying a closed coke guide. The coke guide is movable into a cooperative position against the face of a coke oven after the oven door is removed and into coactive position with the hood. An effluent collecting main is fixed in position alongside the battery and it has a plurality of fume doors that are each disposed opposite a respective oven chamber.

A movable collar on the hood portion cooperates with the effluent collecting main to form a seal. The mechanism which moves the collar into cooperative position with the collecting main also opens a respective fume door in the main. Adjustable curtains or seal plates are mounted to the hood and they are movable as is the collar to form a seal with the hood and the quenching car. The quenching car, of course, moves relative to the hood.

And so, it is to the control of the relative movements of this and similar apparatus that the present invention is directed.

2

To begin with, it is assumed that the pusher machine and the coke guide have been spotted in position opposite the oven to be pushed, and that the door machines on each side have already removed the pusher side and the coke side doors.

Now, it is to be understood, there are three main elements of the apparatus described in the aforementioned application that must be operated in controlled sequence. They are: (1) a pivotable door in the collector or fume main opposite each oven to be pushed; (2) a butterfly or atmospheric vent valve in the collector or fume main; and (3) a damper in the fan suction line that regulates the suction or partial vacuum in the fume main. The system which controls the sequential operation of these three elements is described hereinafter with the aid of the drawing to which reference is made.

In FIGS. 1 and 1a, the coke guide 10 engages and closes a limit switch CGLS when the coke guide contacts and seats against the face of the oven. Activation of switch CGLS starts the sequence of events described hereinafter. But such sequence may be purposely delayed if desired by an operator who may activate a sequence-delay start switch 12.

Initially, when no oven is being pushed, the collecting main 17 is under a partial vacuum or internal negative pressure. The butterfly 15 is closed and the damper 21 is at the minimum open position, which means that it is open just enough to allow some effluent to pass through it; the fume doors, of course, being closed.

When switch CGLS closes, a signal RSB is sent to the transmitter (so marked) located on the door machine support which is movable. Timers TA and TB are both energized.

Received signal RSB contact passes through the transmitter through collector rails, through an electric coupler between the rails of the door machine, to a receiver (so marked); the latter three items being fixed and immovable. From the receiver, signal RSB travels through RS1 to and energizes a butterfly valve cylinder control (so marked). The control cylinder acts through linkage 11, 13, shown schematically, to open and also to close a butterfly or atmospheric vent valve 15 in a collector or fume main 17.

The purpose of the butterfly or atmospheric vent valve 15, when opened, is to reduce the amount of negative internal pressure or partial vacuum in the collector or fume main 17, whereby the door 16 on the fume main opposite the oven to be pushed can be opened more easily. Effluent gases that flow into the fume main 17 pass into a gas scrubber (not shown) in the normal way.

In FIGS. 1 and 1a, a suction fan 18 is shown diagrammatically in the collector main 17, and it is understood that the fan 18 operates continually. The amount of suction or partial vacuum impressed on the collecting or fume main 17 is controlled by the butterfly or atmospheric vent valve 15 and by a movable fan damper 21. The fan damper 21 is normally at minimum open position when no pushing of coke takes place and its position is adjusted, as required, before, during and after pushing.

At this point in time in the pushing sequence, subsequent to the closing of the limit switch CGLS, the atmospheric vent valve 15 is fully open. Timer TA, which was activated upon closing the limit switch CGLS, is so set that it times out and signals a control cylinder 20 having linkage 22 connected to the fume door 16; whereby the fume door opens in timed delay sequence after the butterfly valve 15 has had time to open. The fume door 16 opens simultaneously with advancement of the aforementioned adjustable collar portion of the hood into cooperation with the fume main 17.

As the fume door 16 approaches the fully open position, it engages a door open limit switch, LS, and activates signal RS1 at the transmitter. Thereafter, signal RS1 at the

receiver opens a contact on the butterfly valve open control and closes a contact at the butterfly valve close control. The butterfly valve 15 then closes.

Thereupon, a signal is sent to the fan damper motor control (so marked), and the fan damper 21 opens to a maximum controlled opening since contacts RSB and RS1 are closed. There is, then, maximum designed partial vacuum or suction in the fume main 17 which is ready to receive emissions during pushing.

Pushing then proceeds as scheduled.

After the pushing is completed, the coke guide is moved back away from contact with the face of the coke oven, and the limit switch CGLS opens. The electrical path to RSB and RS1 is also opened. Signal RS1 becomes deactivated, but signal RSB will be held activated by the delayed operation of timer TB until the limit switch CGLS closes to timer circuit TX.

Loss of signal RS1 at the receiver causes the butterfly valve cylinder control to be energized and the linkage 11, 13 moves to open the butterfly valve 15. Simultaneously, the fan damper motor control is deactivated and the fan damper motor operates and closes the damper 21.

The fume main door is open at this point of time in the sequence, and when timer TX times out, the fume door close control cylinder is energized to close the door, and signal RS2 is activated. Signal RS2 at the receiver assures that the butterfly valve close control is inoperative.

When the fume main door is closed, a door-closed limit switch (so marked) is closed and a switch 23 opens which deactivates timer TX, thereby cancelling the signals RSB and RS2. When signals RSB and RS2 are cancelled, as well as all signals to the transmitter and to the receiver, the close-control cylinder connected to the butterfly valve operates to close the butterfly valve 15. Also, the signal RS1 is cancelled, whereupon, the fan damper motor control is activated to close the fan damper.

A manual over-ride signal selector (not shown) is available on the door machine to signal the required operation of the butterfly valve and fan damper control.

From the foregoing description of the embodiment of my invention, those skilled in the art should recognize many important features and advantages of it, among which the following are particularly significant:

That the system is simple in construction, but yet it is to ensure that the elements of an emissions control system function in a proper sequence for the prevention of emission of effluent to the atmosphere; and

That the system is simple in construction, but yet it is effective and easy to install.

Although the invention has been described herein with a certain degree of particularity it is understood that the present disclosure has been made only as an example and that the scope of my invention is defined by what is herein-after claimed.

What is claimed is:

1. In a system for conducting effluent emitted during pushing of coke from a coke oven chamber through a closed coke guide having a hood that conveys said effluent toward a collecting main, which internally is under a partial vacuum or negative pressure, and which has a plurality of pivotable doors, with one such door being disposed opposite each respective coke oven chamber, the improvement in such system comprising:

(a) a system for controlling the movement of the door in said main located opposite an oven to be pushed including:

(i) switch means that is actuated when said coke guide forms a closed flow path for the effluent between said hood and the collecting main;

(ii) means acting responsive to a signal generated when said switch is actuated for decreasing the amount of said vacuum or negative internal pressure in said collecting main;

(iii) means opening said door in timed sequence after said internal vacuum or negative pressure has been decreased; and

(iv) means for thereafter increasing the partial vacuum or negative pressure in said collecting main whereby the effluent emissions created during pushing flow through said opened door and the hood into said collecting main.

5 2. The invention of claim 1 wherein the means opening said door is:

(a) a timer connected in circuitry with said one door whereby said door is actuated on a selected time schedule.

10 3. The invention of claim 1 wherein the means acting responsively to a signal is:

(a) a cylinder control having linkage connections to vent control means in said collecting main whereby, when said vent control means opens, said vacuum or negative pressure in said main decreases.

15 4. The invention of claim 3 wherein the means opening said door in timed sequence includes:

(a) a timer connected in circuitry with a control cylinder linked to said fume door for actuating said door; and

(b) means connected in circuitry with said switch means for activating said timer when said switch means is actuated.

20 5. The invention of claim 3 wherein the means for increasing the partial vacuum includes:

(a) means for deactivating a timer connected in circuitry with said cylinder control whereby said cylinder control is activated and the linkage connected thereto moves to close said vent control means whereby said vacuum or negative pressure in said fume main increases.

25 6. In a system for conducting effluent emitted during pushing of coke from a coke oven chamber through a closed coke guide having a hood that conveys said effluent toward a collecting main, which internally is under a partial vacuum or negative pressure, and which has a plurality of pivotable doors, with one such door being disposed opposite each respective coke oven chamber, the improvement in such system comprising:

(a) a system for controlling the movement of the door in said main that is located opposite an oven to be pushed including:

(i) a first limit switch that is actuated when said coke guide forms a closed flow path for effluent between said hood and the collecting main;

(ii) a first timer, connected in circuitry with said switch and a first control cylinder, that is activated for timing apparatus functions connected in circuitry therewith when said limit switch is actuated;

(iii) said first control cylinder being connected to said door for opening and closing the same when said first timer is activated;

(iv) a second control cylinder connected in circuitry with said limit switch and to valve means associated with said collecting main for regulating the partial vacuum or negative pressure in said main, whereby when said limit switch is actuated said second control cylinder actuates said valve means the partial vacuum or negative pressure therein is reduced;

(v) a second limit switch actuatable by said door when it opens whereby a signal is sent in circuitry connected with said second limit switch to said second control cylinder which is actuated to close said valve means so that the partial vacuum or negative pressure in said main increases;

(vi) means in said fume main for regulating the flow of effluent therethrough, which means assumes a full-flow position in response to a signal sent to it when said valve means moves and

- the partial vacuum or negative pressure increases;
- (vii) means opening said first limit switch whereby said second control cylinder is actuated and opens said valve means whereby the partial vacuum or negative pressure in said fume main decreases;
- (viii) means acting responsively to the opening of said first limit switch whereby said means for regulating the flow of effluent in said fume main closes; and
- (ix) said first control cylinder acts responsively to said first timer after it has performed a pre-selected timing function, whereby said door closes and while closing actuates said second limit switch, whereby said second control cylinder is actuated and said valve means closes and simultaneously said means for regulating the flow of effluent in said fume main opens.

7. In the method for controlling the flow of emissions into a collecting main under negative pressure or partial vacuum that evolve while pushing coke from a coke oven, the improvement comprising the steps:

- (a) advancing a coke guide into position at an oven to be pushed and;
- (b) activating a first control timer that is preset to complete a preselected time cycle, and simultaneously;
- (c) actuating a control cylinder and opening valve means in said collecting main thereby reducing the negative pressure or partial vacuum in said collecting main;
- (d) actuating means that responds to a signal from said first timer and opening an emissions flow-through door in said collecting main;
- (e) opening a damper in said collecting main and increasing said vacuum therein; and
- (f) simultaneously closing said valve means in said collecting main and thereby increasing the vacuum in said main whereby said emissions are drawn into said main.

8. The invention of claim 7 including the steps of:

- (a) retracting said coke guide after the pushing of coke is completed, thereby actuating said means and;
- (b) opening said valve means in said main;
- (c) actuating a second control timer that is preset to complete a preselected time cycle, and simultaneously;
- (d) closing said damper;
- (e) actuating means that responds to a signal from said second timer and closes said emissions flow-through door;
- (f) opening said damper; and
- (g) closing said valve means thereby restoring the vacuum in said collecting main.

9. In the method for controlling the flow of emissions into a collecting main under negative pressure or partial vacuum that evolve while pushing coke from a coke oven, the improvement comprising the steps:

- (a) advancing a coke guide into position at an oven to be pushed and actuating a first switch; thereby;

- (b) energizing both a first and a second timing apparatus each of which is set to delay the sequence of operations according to a preselected time sequence;
- (c) transmitting a signal to and actuating a control cylinder thereby opening valve means on said collecting main and reducing the partial vacuum therein;
- (d) activating means in response to a signal from said first timer for opening a door in said collecting main opposite the oven to be pushed whereby effluent arising from coke pushed through said coke guide flows into said collecting main and simultaneously;
- (e) actuating a second switch whereby signal is transmitted in circuitry to said control cylinder whereby it operates to close said valve means on said collecting main;
- (f) actuating means controlling the partial vacuum or suction in said collecting main whereby the maximum designed partial vacuum or suction therein is restored;
- (g) pushing coke from said oven whereby effluent generated thereby flows into said collecting main; and thereafter;
- (h) retracting said coke guide and thereby de-actuating said first switch and actuating said second timer; and thereby;
- (i) transmitting a signal to and actuating said control cylinder thereby opening said valve means on said collecting main and reducing the partial vacuum; and simultaneously;
- (j) actuating said means controlling the partial vacuum or suction in said main and thereby decreasing said partial vacuum or suction in said collecting main;
- (k) activating said means in response to a signal from said second timer and thereby closing said door in said collecting main and simultaneously actuating a switch;
- (l) transmitting a signal, as a result of closing said switch, to and thereby actuating said valve means in said main and thereby increasing and vacuum or suction; and
- (m) actuating simultaneously said means controlling the partial vacuum or suction in said collecting main whereby normal designed partial vacuum or suction is restored in said collecting main.
